PATENTED MAY 14, 1907.

P. S. SMITH.

MACHINE FOR GLUING BLANKS.

APPLICATION FILED JUNE 12, 1905.

2 SHEETS—SHEET 2.

UNITED STATES PATENT OFFICE.

PHILIP S. SMITH, OF PHILADELPHIA, PENNSYLVANIA, ASSIGNOR TO STOKES & SMITH COMPANY, OF PHILADELPHIA, PENNSYLVANIA, A CORPORATION OF NEW JERSEY.

MACHINE FOR GLUING BLANKS.

No. 853,480.

Specification of Letters Patent.

Patented May 14, 1907.

Application filed June 12, 1905. Serial No. 264,956.

To all whom it may concern:

Be it known that I, PHILIP S. SMITH, a citizen of the United States, residing at Philadelphia, in the county of Philadelphia and State of Pennsylvania, have invented new and useful Improvements in Machines for Gluing Blanks, of which the following is a specification.

My present invention relates to certain new and useful improvements in machines for gluing blanks, and it has for its prime object to provide a machine of very simple construction for applying a uniform coating of glue to the entire surface of one face of a blank during its passage in one direction over a single glue-applying roller and for preventing the said blank from adhering to and wrapping around the roller during the glue-applying operation.

In manufacturing paper boxes having an applied covering (generally a sheet of relatively thin paper) the practice in general use is to form the box and then apply a blank formed of a sheet of thin paper to the surface of the formed box, one surface of the blank being coated with glue before application to the box. In order that the covered box should be smooth and free from blisters, etc., it is essential that the entire surface of the blank receive the glue coating and that the coating be applied evenly. Owing to the fact that great difficulty is had in so coating the surface of the blank with the glue, due to several causes, among which is the fact that the material of the blank is of such a nature that the application of the glue tends to soften the paper, and the further fact that the application of the glue causes the blank to curl, etc., especially when the application is by bringing the surface into contact with a glue-carrying roller, the application of glue to the surface of the blank is generally performed manually. The application of glue to the surface of the blank manually is not only a slow and tedious operation, but it has been found that the coating is unevenly distributed. Hence it is not possible to form uniformly-coated blanks in this manner. By providing a machine which will apply the coating of glue to the blank rapidly and uniformly throughout the entire surface of the blank a great saving of time and expense in the manufacture of the box will be had,

thereby decreasing the relative cost of the completed box.

Briefly and generally stated, the invention comprises a glue tank, a glue distributing roll rotatably mounted therein, a glue applying roller rotatable in surface contact with the said distributing roll and receiving a coating of glue therefrom, a presser roller located above and always out of contact with the glue applying roller, and a plurality of stripper wires or strands located between the glue applying and presser rollers, respectively, and extending transversely to the axis thereof, said wires or strands serving to prevent the sheets or blanks fed to the machine from adhering to and wrapping about the glue applying roller.

The invention further comprises a novel construction of glue applying roller, which is preferably, but not necessarily, made of some suitable compressible or elastic material, such as rubber or rubber composition, said roller having suitably spaced, relatively narrow peripheral grooves and stripper wires, strands or bands extending transversely to the axis of said roller and arranged in line with the grooves therein, the width of the said wires, strands or bands being substantially the same as the width of the peripheral grooves, whereby to provide a substantially continuous or unbroken surface throughout the length of the glue applying roller at the point where the said wires, strands or bands cross the latter, in order that a sheet or blank, when passed over the same, will receive a continuous coating of glue.

The invention further comprises means for individually tightening or tensioning the several stripper wires, strands or bands, and for maintaining them taut, in order that they may the more effectually perform their function.

Finally, the invention consists in the improved construction and combination of parts hereinafter fully described and illustrated in the accompanying drawings, and then definitely pointed out in the appended claims.

In the annexed drawings: Figure 1 is a top plan view of the principal part of a gumming machine, constructed in accordance with my invention; Fig. 2 is a front end elevation; Fig. 3 is a transverse vertical section; Fig. 4

is an enlarged transverse section of portions of the glue-applying roller, the presser roller, and one of the stripper wires or strands; Fig. 5 is a similar view in longitudinal section; 5 and Figs. 6 and 7 are views similar to Figs. 4 and 5, showing a slightly modified form of stripper.

Referring to the drawings, the reference numeral 1 designates a glue tank of any preferred construction, in which is rotatably mounted a glue distributing roll 2, said roll being mounted upon a shaft 2^a, the ends of which are journaled in vertically adjustable bearing plates 3, said plates being adjustable by means of thumb-screws 4, passing through threaded apertures in lugs 5, extending from the sides of the tank, all as clearly shown and described in the Letters Patent granted to me on the 28th day of April, 1903, No. 726,473.

Journalized in suitable bearings formed in the vertical side plates 6 extending upward from the opposite sides of the tank 1, is a glue applying roller 7 of novel construction, presently to be described in detail, said roller being in surface contact with the glue distributing roll 2. Also journalized in open bearings in the side plates 6, is a presser roller 8, said roller being arranged directly above and always maintained out of contact with the glue-applying roller 7. As will be seen by referring to the drawings, the presser roller 8 is mounted in open bearings so that the same may be readily removed and replaced when desired.

The means for rotating the glue distributing roll 2, the glue-applying roller 7, and the presser-roller 8, will now be described. Loosely mounted upon a pin 9 fixed to one of the side plates 6, is a rotatable sleeve 10, carrying a pinion 12 and a clutch member 13. Also loosely mounted for rotation on the pin 9, is a longitudinally movable sleeve 14 having fixed thereto a pulley 15, which may be driven from any suitable source of power. A clutch lever 16 pivoted at 17 to a bracket extending outward from one of the side plates 6, has its lower end 18 in engagement with a groove in the sleeve 14, and is so constructed that the sleeve 14 may be shifted longitudinally on the pin 9, so as to bring the clutch face 19 on said sleeve into or out of engagement with the clutch 13 on the sleeve 10, whereby the pinion 12 may be rotated or stopped, as desired. Fixed to one end of the shaft carrying the roll 7 is a gear wheel 20, which is in mesh with the pinion 12 on the sleeve 10, and secured to the opposite end of the shaft of the glue applying roller 7 is a pinion 21, which is in mesh with a gear wheel 22 mounted on the shaft 2^a of the glue distributing roll. Mounted on the shaft 23 of the presser roller 8 is a pinion 24, which is in mesh with the gear 20. By the gearing described, it will be seen that when the clutch

faces 13 and 19 are in engagement, the pinion 12 will cause rotation of the glue distributing roll 2, the glue-applying roller 7, and the presser roll 8, in the direction of the arrows indicated in Fig. 3. A suitable table 25 for the blanks to be gummed may be employed, such a table being shown in Fig. 3 of the drawing.

In coating blanks or separate sheets with a machine of the type herein described, the custom is to feed a number of superposed blanks through the machine at once, or a single blank with a sufficiently stiff backing. These blanks are passed between the glue applying roller 7 and the presser roller 8 by hand, and the bottom blank receives its coating of glue from the glue applying roller, the presser roller acting to impart sufficient pressure to the package of blanks or to the single blank and its backing, in order that a smooth and even application of the adhesive may be obtained. It will be apparent that unless some means is provided to prevent it, the blank being gummed will adhere to the glue-applying roller and wrap about the same, which would render the machine totally inoperative for the purpose intended. One of the salient features, therefore, of the present invention, is the provision of means to prevent the blank being gummed, from adhering to the glue applying roller, as set forth, and this means comprises a novel construction and arrangement of strippers now to be described.

Extending transversely across the front of the machine and parallel with the glue-applying roller 7, is a plate or bar 26, provided with a plurality of pins 27. A similar plate or bar 28 extends transversely of the machine in rear of the glue applying roller 7. In this plate 28, and in alignment with each of the pins 27 in the plate 26, are the screws 29, each provided with a lock nut 30. Attached to each pair of pins 27 and screws 29, is a relatively narrow stripper, strand, or wire 31, there being a plurality of these strands or wires which extend on opposite sides and across the upper face of the glue applying roller 7, the wires being spaced apart a suitable distance to meet proper requirements. It will be apparent that by properly turning the screws 29, the individual strands or wires 31 may be brought to proper tension and afterward secured taut by means of the lock nuts 30.

The glue applying roller 7 is preferably, but not necessarily, composed of some suitable compressible or elastic material, such as rubber, and is provided with a plurality of circumferentially arranged, peripheral ways or grooves 32, the diameter of the grooves being substantially the same as the width of the stripper wires or strands 31, as clearly shown in the enlarged sectional view, Fig. 5. In other words, the stripper strands or wires

substantially fill the grooves in the roller 7, at the point where they cross the latter. By this arrangement it will be apparent that as the wires or strands are very narrow, and as these elements substantially fill the peripheral grooves 32, a smooth and unbroken surface will be provided at the point on the glue applying roller opposite the presser roller, and from which the blank receives its supply 10 of glue, so that in operation the blank will receive a continuous coating of glue, as distinguished from a striped coating, which would be the case if the strands or wires were wider than the grooves in the glue applying 15 roller.

While I prefer to provide the glue applying roller with circumferential grooves as shown and described, I have found that fairly good results may be obtained by dispensing with 20 such grooves, especially where the glue applying roller 7 is made of rubber or some other elastic or compressible material, it being apparent in this case, that the stripper wires or strands will be pressed down into the 25 surface of the said roller whenever a package of blanks is passed through the machine, this being possible owing to the fact that the stripper strands or wires are relatively fine or narrow.

In Figs. 6 and 7 I have shown a slightly modified form of stripper. In these figures the reference numeral 33 designates a cross plate corresponding to the plate 26 of the other construction, and the numeral 34 designates a plate corresponding to the plate 28 of the construction before described. Projecting upward from the plate 33, is a series of pins 35, one for each stripper, and extending upward from the plate 34 is a series of screws 40, each having a threaded engagement with the plate 34, and each provided with a lock-nut 37. In this instance, the stripper consists of a very thin steel strap 38, which is provided at one end with a loop through which one of the pins 35 extends, its other end being passed through an elongated slot in one of the screws 36. Obviously, by turning the screw 36, the strap 38 may be drawn taut and held so by the lock nut 37. When 50 employing the steel strap construction as described, the glue applying roller will be provided with narrow peripheral grooves of sufficient width only to receive the same. This latter construction has the advantage 55 over the fine wire construction of being stronger and having more lasting qualities.

I am aware that it is not broadly new to provide a machine for gluing blanks, wherein is employed a peripherally grooved glue applying roller with stripper rods extending into the said grooves to prevent the blanks from adhering to and wrapping about the said roller. In the known constructions, however, the said peripheral grooves are relatively wide, as compared to the width of the

stripper rods, and the blank being gummed therefore does not receive a continuous or unbroken coating of adhesive, but to the contrary, is coated in stripes. The present invention is clearly distinguished from the said prior devices in that the stripper wires or strands are of a width substantially equal to the grooves and the upper surface thereof is preferably flush with the upper surface of the roller at a point where the strands or wires 75 enter the grooves, so that a continuous surface is provided where the roller transmits its glue to the blank.

While I have shown and described the glue-applying roller as receiving its supply of 80 glue from a distributing roll rotatably mounted in the glue tank, I do not wish to be understood as limiting myself to this specific manner of applying the glue to the said roller. Obviously, the glue applying roller 85 may receive its coating of glue otherwise, without departing from the spirit of the invention as defined in the appended claims.

Having thus described my invention, what I claim as new and desire to secure by Letters 90 Patent is:—

1. In a machine of the character described, a glue applying roller of elastic or compressible material, means for applying glue to said roller, a plurality of strippers of 95 fine gage arranged above and transverse to the axis of said glue applying roller, and a pressure roll located above and normally out of contact with said strippers, the construction and arrangement of parts being such 100 that the strippers will be caused to be embedded in the glue applying roller when pressure is exerted thereon by the passage of blanks through the machine.

2. In a machine of the character described, a glue tank, a glue applying roller of 105 elastic or compressible material rotatably mounted in said tank, a pressure roll located above and normally out of contact with the glue applying roller, and a plurality of tensioned stripper wires of fine gage arranged 110 between and extending transverse to the axis of said roller and roll, said stripper wires being adapted to be embedded in the glue applying roller at the point where they cross 115 the latter when pressure is applied thereto by the action of the pressure roll upon the blanks as they are passed through the machine.

3. In a machine of the character described, a glue tank, a glue roll rotatably 120 mounted therein, a glue applying roller in surface contact with said roll, a presser roller located above and out of contact with the glue applying roller, a plurality of stripper wires or strands arranged above and transversely to the axis of said glue applying 125 roller, and means for tensioning the said stripper wires or strands.

4. In a machine of the character described, a glue applying roller having a plurality 130

- of circumferentially arranged peripheral grooves, and strippers arranged transversely to the axis of the roller, said strippers being arranged in line with and substantially filling the grooves of the roller at the point where they cross the latter.
5. In a machine of the character described, a glue applying roller having a plurality of circumferentially arranged peripheral grooves, and strippers arranged transversely to the axis of the roller and extending on opposite sides thereof, said strippers being arranged within and substantially filling the grooves of the roller.
10. 6. In a machine of the character described, a glue applying roller of elastic material having a plurality of circumferentially arranged peripheral grooves, and a plurality of relatively fine stripper wires or strands arranged transversely to the axis of said roller and extending on opposite sides thereof, said wires or strands lying in the plane of the grooves and substantially filling the latter at the point where they cross the roller.
15. 7. In a machine of the character described, a glue tank, a glue distributing roll rotatably mounted therein, a glue applying roller of elastic material arranged above and in surface contact with the said distributing roll, said roller being provided with a plurality of circumferentially arranged peripheral grooves, a plurality of relatively narrow strippers arranged transversely to the axis of the said roller and extending on opposite sides thereof, said strippers being embedded in and filling the grooves at the point where they cross the roller, and a presser roller located above and out of contact with the said glue applying roller.
20. 8. In a machine of the character described, a glue tank, a glue distributing roll rotatably mounted therein, a glue applying roller of elastic material arranged above and in surface contact with the said distributing roll, said roller being provided with a plurality of circumferentially arranged peripheral grooves, a plurality of relatively narrow strippers arranged transversely to the axis of the said roller and extending on opposite sides thereof, said strippers being embedded in and filling the grooves at the point where they cross the roller, means for adjusting the tension of the strippers, and a presser roller located above and out of contact with the said glue applying roller.
25. 9. In a machine for applying glue to blanks, a glue tank, a glue distributing roll rotatably mounted in said tank, a glue applying roller in surface contact with said roll, a presser roller located above and out of contact with the glue applying roller, a plurality of stripper wires or strands arranged above and transversely to the axis of the said glue applying roller, fixed supports on opposite sides of the last-named roller, and adjustable

means carried by said supports for retaining and individually adjusting the said strippers.

10. In a machine for coating one surface of sheet material or a blank made therefrom with an adhesive comprising means for applying an unbroken film of the adhesive to one surface of a moving sheet or blank during its movement in one direction, and means embedded in the adhesive-applying means for supporting the sheet or blank while moving and separating or stripping it from the adhesive-applying means after it has received the adhesive coating.

11. A machine for coating one surface of sheet material or a blank made therefrom, comprising an adhesive-applying roll having parallel circumferential ways therein, a feed roll, and transversely-arranged wires passed between the rolls from front to rear and through the ways and flush with the surface of the adhesive-applying roll.

12. A machine for coating one surface of sheet material or a blank made therefrom, comprising an elastic adhesive applying roll having parallel circumferential ways therein, a feed roll, and supports for the sheet or blank extending from front to rear between the rolls, through the ways and below the bite of the adhesive-applying and feed rolls.

13. A machine for coating one surface of sheet material or a blank made therefrom, comprising an adhesive applying roll having parallel circumferential ways therein, a feed roll, and transversely arranged wires passed between the rolls from front to rear through the ways in the adhesive applying roll to form a support for the blank moving from between the rolls after the adhesive is applied and to support or strip the sheet or blank from the adhesive applying roll.

14. A machine for coating one surface of sheet material or a blank made therefrom with an adhesive, comprising a single elastic adhesive-applying roll having peripheral ways therein, horizontal wire supports for the sheet or blank embedded in the ways the sides of which close tightly about the wire supports, and bars on opposite sides of the adhesive-applying roll to which the ends of the wires are fastened.

15. A machine for coating one surface of a blank of sheet material with an adhesive, comprising a single elastic adhesive-applying roll having peripheral ways therein, and horizontal wire supports for the blank embedded in the ways, the sides of which close tightly about the wire supports.

16. In a machine for applying an unbroken pellicle of adhesive material to one surface of a sheet or blank, comprising a single adhesive-applying roll of elastic or compressible material, and stationary means embedded in and closely embraced by the material of the roll, for stripping the coated blank therefrom.

17. In a machine for applying an unbroken pellicle of adhesive material to one surface of a sheet or blank, comprising a single adhesive-applying roll of elastic or compressible material, and stationary wires of fine gage embedded in and closely embraced by the material of the roll, for stripping the coated blank therefrom.

In testimony whereof I have hereunto set my hand in presence of two subscribing witnesses.
